(57) CLAIM

The ornamental design for a display screen or portion thereof with animated graphical user interface as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof; and,

FIG. 5 is a fifth image thereof.

The outer broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1-5. The process or period in which one image transitions to another forms no part of the claimed design.

The term ZOOM™ forming part of the claimed design is a trademark of Zoom Video Communications, Inc.

1 Claim, 5 Drawing Sheets

The logo consists of the word "ZOOM" in a bold, sans-serif font. The letters are outlined in black and filled with a light gray color. The "Z" is the most prominent, with a large circular dot in the center of the "O". The "O" is also large and has a circular cutout in the middle. The "O" and "M" are connected at the top and bottom.

This is a smaller version of the "ZOOM" logo, showing only the "Z" and the "O" from the previous image. The "Z" has a large circular dot in the center, and the "O" has a circular cutout at the top and bottom.
